UNITED STATES PATENT OFFICE.

JAMES E. JEWELL, OF KANSAS CITY, MISSOURI.

MEASURING AND DELIVERING BIN FOR POTATOES, &c.

1,351,251.

Specification of Letters Patent. Patented Aug. 31, 1920.

Application filed January 16, 1919. Serial No. 271,541.

To all whom it may concern:

Be it known that I, JAMES E. JEWELL, a citizen of the United States, residing at Kansas City, in the county of Jackson and

5 State of Missouri, have invented certain new and useful Improvements in Measuring and Delivering Bins for Potatoes, &c., of which the following is a specification.

This invention relates to measuring and 10 delivering bins for potatoes and the like for use particularly in retail grocery stores, and has for its object to produce a device of this character by which potatoes can be discharged in measured quantities into a basket 15 or paper bag or the like without requiring the clerk to touch the potatoes. A further object is to produce a device which will measure and deliver articles regardless of their size.

20 A still further object is to produce a device of the character outlined which is of simple, strong, durable, and inexpensive construction.

With these objects in view the invention 25 consists in certain novel and useful features of construction and combinations of parts as hereinafter described and claimed; and in order that it may be fully understood reference is to be had to the accompanying drawing, in which:

Figure 1, is a front view of a measuring and discharging bin embodying the invention.

Fig. 2, is a vertical section taken on the 35 line II—II of Fig. 1.

Fig. 3, is a horizontal section taken on the line III—III of Fig. 2.

Fig. 4 is an inverted plan view of the device.

40 Fig. 5, is a vertical section on the line V—V of Fig. 2.

In the said drawing where like reference characters identify corresponding parts in all of the figures, 1 is a hopper shaped bin 45 having a downwardly and forwardly sloping bottom 2 and a front wall 3 which sets back from the front edges of the side walls and terminates a suitable distance above the front edge of the bottom to provide a dis- 50 charge opening 4, which opening is controlled by a slide gate 5 fitting between the lower part of the front wall and a pair of retaining or guide cleats 6 fastened to the side walls.

55 Below the bottom 2 of the bin is a sub-bottom, the same comprising two sections

arranged side by side, one being fixed in position and the other slidable in a forward and rearward direction. The outer edges of the fixed sub-bottom section 7 and the slid- 60 able sub-bottom section 8 respectively rest upon supporting strips 9 secured to the lower edges of the walls of the bin. The outer edges of said sub-bottom sections are spaced from the adjacent side walls of the 65 bin for a purpose which hereinafter appears, and they abut together at their inner edges where they rest upon a supporting strip 10 arranged midway between and parallel with supporting strips 9. The supporting strips 70 9 are rigid with the side walls of the bin and also with the supporting legs 11 of the bin, and the legs are braced apart by braces 11^a, the braces 11^a at the sides forming intermediate supports for the strips 9, and the 75 braces 11^a at the front and back forming supports for the intermediate supporting strip 10.

Resting upon the supporting strips is a bottomless slide drawer, comprising a pair 80 of sides 12 fitting against the side walls of the bin and upon supporting strips 9, a front wall 13 to engage the front edges of the side walls when the drawer is closed, a back wall 14 which when the drawer is closed stands 85 just under the front portion of the bottom 2 of the hopper, and a longitudinal partition 15 extending from the front wall to the back wall; it being noted in this connection that the back wall 14 and the longitudinal wall 15 90 terminate just above the permanent and slid- able sections of the sub-bottom. The sides of the drawer extend a considerable distance beyond the back wall thereof and underlie guide strips 16 secured to the side walls of 95 the bin so as to give the drawer a long bearing and be easy of operation. To limit the forward movement of the drawer, which should stop when the back wall thereof is flush with the front edges of the side walls 100 of the bin, the side walls of the drawer are provided with upwardly projecting stops 17 to abut against the rear edges of the strips 16, and to limit rearward sliding movement of the slidable section of the sub-bottom in- 105 dependent of the closing movement of the drawer, the said slidable section is provided with a step-shaped lug 18 for abutment against one of the angle braces 11^a. Said lug has an additional function in that it 110 normally projects forwardly through an opening in the front wall of the drawer, and

- if it is desired that said slidable section shall move forward with the drawer when the latter is opened, a pivoted hook 19 secured to the outer face of the front wall of the drawer, is engaged with a perforation in the front end of said lug. Lug 18 has a further function in that it acts as a support for the front edge of the slidable sub-bottom 8, the strips 9 and 10 supporting the rear edge, 5 when the slide section 8 is locked to the drawer front, when the drawer is opened.
- From the foregoing it will be apparent that when the drawer is closed and the slide gate 5 is opened, potatoes will fall from the bin into the drawer, the gate being then re-closed. The opening of the drawer will then result in its back wall pushing the potatoes forwardly off the sub-bottom, though if only half the quantity of potatoes is to be 10 discharged, the hook 19 will be engaged with the lug 18 and thus compel the slidable section of the sub-bottom to move forward and hence retain the overlying potatoes while those at the opposite side of the longitudinal partition 15 will be discharged over the front edge of the fixed section of the sub-bottom. When the drawer is closed the engagement of hook 19 with lug 18 prevents the slidable bottom being pushed too far inward, and in this connection it is desired to 15 state that the slidable sub-bottom section 8 engages with sufficient friction the strips 9 and 10 to retain its stationary position when the drawer is pulled forward for the purpose of discharging potatoes therein off the front edge of said sub-bottom, it being clearly understood that the drawer itself has no real bottom and that the sections 7 and 8 take the place thereof.
- 40 To guide the potatoes into a bag or other receptacle supported by hand or upon the floor, a collapsible funnel 20 is provided, the same being preferably of fabric and secured at its upper edge to the front ends of supporting strips 9 and 10 and to the front wall of the drawer so that when the latter is closed the funnel will be flattened and when the drawer is opened the funnel will be open as indicated by dotted lines in Fig. 2, the funnel preferably corresponding in width to the drawer so that it shall be capable of accommodating and guiding the potatoes from either or both sides of the partition 15.
- It will be understood that the drawer is 45 proportioned to accommodate a peck of potatoes or the like, and that with the central partition said measure of potatoes is divided into two half pecks, but it will also be understood that the drawer may be sub-divided to 50 deliver in quarter peck measures if desired or in any other quantities.
- It will be apparent that in the operation of this device the potatoes need not be handled by the clerk, and that the potatoes will 55 be of mixed sizes as they come from the bin.

The provision of a device eliminating the necessity of handling the potatoes is desirable as they are ordinarily dirty and hard on the hands; and it is desirable to sell them as they run from the bin and thus avoid the picking 70 out of the large potatoes and leaving the small ones in the bin to be sold, frequently at a lower price.

From the above description it will be apparent that I have produced a device of the 75 character set forth which possesses all of the advantages hereinbefore mentioned, and I wish it to be understood that while I have illustrated and described what now appears to be the preferred construction I reserve the 80 right to all changes properly falling within the spirit of the appended claims and the scope of the present invention.

I claim:

1. In a device of the character described, 85 a hopper having a discharge opening at its lower end, a gate controlling said opening, a receptacle for receiving from the hopper through said opening and movable for discharging what it receives, and a collapsible 90 funnel openable through opening movement of said receptacle, to receive the contents of the latter, and collapsible through closing movement of the receptacle.

2. In a device of the character described, 95 a hopper having a discharge opening at its lower end, a sub-bottom below and projecting forwardly beyond the discharge opening of the hopper, a receptacle for which when closed, the sub-bottom constitutes a bottom 100 and movable to effect the discharge off said bottom of material entering the receptacle from the hopper, and a collapsible funnel secured at opposite sides to a fixed point of the device and to said movable receptacle 105 and adapted to be opened and closed by opening and closing movement respectively, of said receptacle.

3. In a device of the character described, 110 a hopper having a discharge opening at its lower end, a sub-bottom below and projecting forwardly beyond the discharge opening of the hopper, a receptacle for which when closed, the sub-bottom constitutes a bottom and movable to effect the discharge 115 off said bottom of material entering the receptacle from the hopper, a collapsible funnel secured at opposite sides to a fixed point of the device and to said movable receptacle and adapted to be opened and closed by 120 opening and closing movement respectively, of said receptacle; said sub-bottom comprising two sections arranged side by side one fixed and one movable, said receptacle having a partition dividing it into a compartment 125 for which the fixed section of the sub-bottom forms a bottom and a second compartment and for which said movable section of the sub-bottom forms a bottom and means for detachably connecting said mov-

able section of the sub-bottom with said receptacle to cause said movable section to move with the receptacle and thus constitute a bottom for one compartment thereof regardless of whether said receptacle is in open or closed position.

4. A device of the character described, comprising an elevated hopper having a discharge opening at its lower end, a gate controlling said opening, a sub-bottom underlying and spaced from said hopper and projecting forwardly beyond said opening, a bottomless slide drawer interposed between the hopper and the sub-bottom and closed by the latter when in closed position, the drawer having a back wall adapted when the drawer is open to move forward over the sub-bottom and discharge the contents of the drawer received from the hopper through the discharge opening thereof, off the front end of said sub-bottom, and a collapsible funnel suspended at its front side from the front portion of the drawer and at its rear side from a fixed portion of the device adjacent the front edge of said sub-bottom, to receive and guide downward the contents discharged by said drawer when opened.
5. A device of the character described, comprising an elevated hopper having a discharge opening at its lower end, a gate controlling said opening, a sub-bottom underlying and spaced from said hopper and projecting forwardly beyond said opening, a bottomless slide drawer interposed between the hopper and the sub-bottom and closed by the latter when in closed position, the drawer having a back wall adapted when the drawer is opened to move forward over the sub-bottom and discharge the contents of the drawer received from the hopper through the discharge opening thereof, off the front end of said sub-bottom, a collapsible funnel suspended at its front side from the front portion of the drawer and at its rear side from a fixed portion of the device adjacent the front edge of said sub-bottom,

to receive and guide downward the contents discharged by said drawer when opened; said sub-bottom comprising two sections arranged side by side, one slidable and the other fixed, and said drawer having a longitudinal partition dividing it into two compartments one closed when the drawer is closed, by the movable and the other by the fixed section of the sub-bottom, and means for detachably connecting the slidable section of the sub-bottom with said drawer to move back and forth therewith.

6. A device of the character described, comprising an elevated hopper having the lower portion of its front wall set back of the front edges of the side walls and provided with an opening at the lower end, and a downwardly and forwardly sloping bottom terminating at the lower side of said opening, a gate for controlling the passage of the contents of the hopper through said opening, a sub-bottom suitably supported below and spaced from the hopper and extending forwardly beyond the vertical plane of the discharge opening of the hopper, a slide drawer interposed between the hopper and said sub-bottom, comprising side walls, a front wall connecting the side walls, and a back wall connecting the side walls, said drawer being adapted to receive the discharge from the hopper when said gate is open and to discharge off of the front end of said sub-bottom when the drawer is pulled forward through the pressure applied on its contents by its back wall, and a collapsible funnel suspended at its rear side from a fixed point of the device adjacent the vertical plane of the front edge of said sub-bottom and at its front side from the front wall of the drawer for the purpose of receiving and guiding the contents of the drawer as discharged therefrom by the opening movement thereof.

In testimony whereof I affix my signature,

JAMES E. JEWELL.
